United States Patent Office

Des. 184,550
Patented Mar. 3, 1959

184,550

OUTDOOR THERMOMETER

Ralph C. Wappner, Springfield, Ohio, assignor to The Ohio Thermometer Company, Springfield, Ohio, a corporation of Ohio

Application May 11, 1956, Serial No. 41,447

Term of patent 14 years

(Cl. D52—7)

Fig. 1 is a front view of an outdoor thermometer embodying my new design; and

Fig. 2 is a side view thereof.

I claim:

The ornamental design for an outdoor thermometer, substantially as shown.
